United States Patent Office

Des. 226,581
Patented Mar. 27, 1973

226,581

CIGARETTE LIGHTER

Kenjiro Goto, Tokyo, Japan, assignor to Mansei Kogyo
Kabushiki Kaisha, Kawaguchi-shi, Saitama, Japan

Filed Dec. 27, 1971, Ser. No. 212,851

Term of patent 14 years

Int. Cl. D27—05

U.S. Cl. D48—27

FIG. 1 is a top plan view of a cigarette lighter showing my new design;

FIG. 2 is a front end elevational view thereof;

FIG. 3 is a side elevational view thereof;

FIG. 4 is an elevational view of the side opposite that shown in FIG. 3;

FIG. 5 is a rear end elevational view thereof;

FIG. 6 is a bottom plan view thereof;

FIG. 7 is a front perspective view thereof;

FIG. 8 is a rear perspective view thereof; and

FIG. 9 is a front perspective view of the lighter in an operative condition.

I claim:

The ornamental design for a cigarette lighter, substantially as shown.
